UNITED STATES PATENT OFFICE.

WALTER W. SIBSON, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

TRANSMISSION-CHAIN.

1,316,747.

Specification of Letters Patent. Patented Sept. 23, 1919.

Application filed February 12, 1919. Serial No. 276,676.

To all whom it may concern:

Be it known that I, WALTER W. SIBSON, of Philadelphia, in the county of Philadelphia, and State of Pennsylvania, have invented 5 certain new and useful Improvements in Transmission-Chains, whereof the following is a specification, reference being had to the accompanying drawings.

The invention relates to transmission 10 chains capable of being spirally wound upon a receiving drum or beam in such a way as to prevent interference or overlapping.

The invention is directed to a chain having the above characteristics wherein the 15 link members are arranged parallel to its longitudinal center line, so that the load is evenly distributed.

The structure by which I attain this desideratum will be best understood from the 20 drawings in which Figure I, is a diagrammatic view illustrating the practical application of my improved chain in association with a receiving or winding drum therefor.

Fig. II, is a plan view of a portion of the 25 chain on a larger scale, and,

Fig. III, is a side view thereof.

Referring first to Figs. II, and III, my invention as therein embodied consists of a chain, comprehensively indicated at 1, and 30 composed of a series of link members 2, 2, preferably arranged alternately in groupings of twos and threes forming composite link sections. It is to be understood that these numbers are arbitrarily chosen 35 and may be varied according to the particular use to which such chains are to be applied. As clearly shown in Fig. II, the axes of the pivotal pins 3, by which the interlinking is effected are inclined to the 40 normal, or perpendicular to the center line of the chain, so as to make other than a right angle with said center line. The functional advantage obtained by this construction will be readily understood from Fig. I,

wherein I have shown a receiving drum or 45 beam 10, upon which the chain is adapted to be wound. During the rotation of the drum, the chain automatically collects spirally thereon, the pitch of the spiral being determined by the inclination of the pivotal 50 pins for the links. The accumulation upon the receiving drum will thus be evenly distributed lengthwise thereof without danger of interference or overlapping between successive turns.

I am aware that the same results have heretofore been accomplished by offsetting successive links or groups of links in a predetermined order but in such designs, the pivotal axes of the links have been maintained at right angles to the longitudinal line or center line of the chain. My improved construction differs essentially from the previous designs in that its chief characteristics reside in the inclination of its pivotal axis as hereinbefore described, while at the same time, perfect symmetry of loading is secured with respect to the longitudinal outer line and the load more evenly distributed throughout the length of the chain as 70 a consequence.

Having thus described my invention, I claim:

1. A linked transmission chain having the pivotal axes of its links inclined to the 75 normal.
2. A composite transmission chain having its links parallel with its longitudinal line and the pivotal axes of the links inclined to the normal.

In testimony whereof I have hereunto signed my name, at Philadelphia, Pennsylvania, this fourth day of February, 1919.

WALTER W. SIBSON.
